HARMONICA HOLDER

Henry Sherman, West Coxsackie, N. Y.

Application March 12, 1937, Serial No. 130,589

3 Claims. (Cl. 84—379)

This invention relates to a harmonica holder and particularly to that type of holder that serves to support the harmonica either in a position for operation or in an out-of-the-way position.

5 An object of the present invention is to improve upon the types of harmonica holders now used or known in the art; and the invention together with its objects and advantages will be best understood from a study of the following 10 description taken in connection with the accompanying drawings wherein:—

Figure 1 is a side elevational view of a harmonica holder embodying the features of the present invention, the same being shown in an 15 operative position.

Figure 2 is a plan view of the harmonica holder with certain parts omitted.

Figure 3 is an elevational view of a clamp assembly forming part of the invention.

20 Figures 4 and 5 are detail views taken substantially on the lines 4—4 and 5—5, respectively, of Figure 3; the spring and nut of Figure 3 being omitted in Figure 4.

Figure 6 is a fragmentary perspective, exploded 25 view substantially illustrating the pivotal connection between the stationary and swinging frames embodied in my improved construction, the spring and nut forming part of this connection being omitted.

30 Figure 7 is a fragmentary detail sectional view further illustrating the pivotal connection between the frames.

Figure 8 is a detail sectional view taken substantially on the line 8—8 of Figure 2.

35 Figure 9 is a view showing in top plan a clamp jaw with the hook associated with the jaw shown in transverse section.

Referring to the drawings by reference numerals, it will be seen that in the preferred embodiment thereof the holder consists of what may be 40 termed a stationary or neck embracing frame 5 and a swinging frame 6.

The frame 5 is provided with a curved or neck portion 7 adapted to fit substantially snugly 45 around the neck of an operator and outwardly curving end portions 8 terminating in eyes 9. Preferably the stationary or neck embracing frame 5 is encased in a sheathing 10 of rubber or other suitable material.

50 The frame 6 is substantially U-shaped the sides of which have outwardly and longitudinally extended end portions 11 that terminate in threaded journal extensions 12 that extend through the eyes 9 and are equipped with thumb nuts 13. Disposed on the journal extensions 12

are coil springs 14 whereby, by tightening the nuts, the springs 14 cooperate therewith and the frames 5 and 6 may be held at the desired angular adjustment relative to one another.

5 The invention further comprehends the provision of an improved harmonica clamp indicated generally by the reference numeral 15.

The clamp 15, in the preferred embodiment thereof, consists of an attaching bar 16 from which rise short posts 17 connected at their upper ends by a bar or rod 18. Rigidly secured to the bar 18 in any suitable manner is a fixed clamping plate or jaw 19.

Slidable between the posts 17 is a rod 20 provided at its respective opposite ends with hooks 21 that engage the post 17 as shown in Figures 3 and 5. Rigidly secured to the rod 20 is a sliding clamping plate or jaw 22 cooperable with the clamping plate 19 for clamping therebetween 10 the part of the harmonica 23 inserted between 15 the clamping plates.

Intermediate its ends the bar 16 is provided with a downwardly offset portion provided with a threaded aperture through which threads the stem of an adjusting bolt 24. As shown the head 25 24 of the bolt 24 is in the form of a cup to receive one end of a coil spring 25 the other of which spring is suitably engaged with an underside of the clamping plate 22. Obviously by threading the nut upwardly or downwardly rod 30 20 with plate 22 associated therewith is caused to move toward or away from the plate 19 to secure or release the part of the harmonica inserted between the plates.

At its respective opposite end the bar 16 is 35 provided with hooks 26 that engages the straight parallel portions of the sides of the frame 6 adjacent the closed end of the frame; and the upper clamping plate 19 has struck out therefrom a hook 27 that engages over the closed end of the 40 frame 6 in a manner suggested in Figure 1 whereby the clamp device 15 is releasably secured on the frame 6 at the closed end thereof for supporting the harmonica, in a manner clearly shown in Figure 1 so that the operator may play 45 on the harmonica as desired.

When the harmonica is not in use frame 6 may be swung downwardly to position the harmonica so that the same will not interfere with the operator playing another type of musical instrument.

It is thought that a clear understanding of the construction, utility and advantages of an invention of this kind will be had without a more detailed description.

Having thus described the invention what is claimed as new is:—

1. In a harmonica holder, a neck embracing frame, a second frame hinged to the neck embracing frame for supporting a harmonica, a clamp, interengaging means on the clamp and the second frame for detachably securing the clamp to the last-mentioned frame, and said clamp including a frame structure, a fixed clamping plate on said frame structure, a movable clamping plate slidably mounted on the frame structure of said clamp and movable thereon toward and away from the fixed clamping plate and a spring acting on the movable clamping plate for moving the latter to a clamping position, a screw threaded through a part of said clamp frame, said screw having a cup-shaped head, and said spring being interposed between said screw and said movable clamping plate and having an end engaging in the head of said screw.
2. A harmonica holder comprising a frame adapted to fit around the neck of the person using the device, said frame being provided at its ends to form a pair of eyes, a substantially U-shaped front frame formed with right angle projections at its ends, said projections being threaded and extending through said eye members, wing nuts threaded on said projections, and springs disposed on said projections between said wing nuts and said eyes, and a harmonica clamping device mounted on the front frame adjacent the closed end thereof, said clamping device including a bar provided at its respective opposite ends with hooks to engage the sides of the U-shaped front frame, posts extending from said bar in parallelism, a fixed clamping plate supported between said posts, a second clamping plate provided at its respective opposite ends for engagement with said posts for supporting the second clamping plate for movement toward and away from the fixed clamping plate, a bolt threaded through an opening in the end hook-equipped bar, and a spring disposed between the head of the bolt and the movable clamping plate and acting on the latter for moving the same to a clamping position and a hook extending from the clamping plate and adapted to engage the U-shaped front frame at the closed end of the U.

plate provided at its respective opposite ends for engagement with said posts for supporting the second clamping plate for movement toward and away from the fixed clamping plate, a bolt threaded through an opening in the end hook-equipped bar, and a spring disposed between the head of the bolt and the movable clamping plate and acting on the latter for moving the same to a clamping position.

3. A harmonica holder comprising a frame adapted to fit around the neck of the person using the device, said frame being provided at its ends to form a pair of eyes, a substantially U-shaped front frame formed with right angle projections at its ends, said projections being threaded and extending through said eye members, wing nuts threaded on said projections, and springs disposed on said projections between said wing nuts and said eyes, and a harmonica clamping device mounted on the front frame adjacent the closed end thereof, said clamping device including a bar provided at its respective opposite ends with hooks to engage the sides of the U-shaped front frame, posts extending from said bar in parallelism, a fixed clamping plate supported between said posts, a second clamping plate provided at its respective opposite ends for engagement with said posts for supporting the second clamping plate for movement toward and away from the fixed clamping plate, a bolt threaded through an opening in the end hook-equipped bar, and a spring disposed between the head of the bolt and the movable clamping plate and acting on the latter for moving the same to a clamping position and a hook extending from the clamping plate and adapted to engage the U-shaped front frame at the closed end of the U.

HENRY SHERMAN.
